[57] **ABSTRACT**

A new liquid detergent system is disclosed wherein a compound of the formula:

is employed as a bacteriostat. A novel method of solubilizing this bacteriostat in the liquid detergent system is also disclosed.

3 Claims, No Drawings

NOVEL LAUNDERING COMPOSITIONS

This application is a continuation-in-part of Ser. No. 258,153 filed May 31, 1972, now abandoned.

BACKGROUND OF THE INVENTION

1. Field of the Invention

This invention relates to a novel liquid detergent system that exhibits bacteriostatic action. More particularly, it relates to such a system that contains 2,4,4'-trichloro-2'-hydroxy-diphenyl ether as an active bacteriostat. Additionally, this invention deals with a unique method for solubilizing the above bacteriostat in a liquid detergent system.

2. Description of the Prior Art

It has long been known that it is desirable to include some type of bacteriostat in detergents and soaps to prevent bacteria growth and to sanitize fabrics. Over the years there have appeared numerous commercial products that have been somewhat effective in controlling the growth of undesirable bacteria. These products usually fall into three categories, namely, hexachlorophene, halogenated carbanilides and tribromosalicycyl-

and their use as bactericidals. This patent discloses that a preferred use for these compounds is in disinfecting goods which are washed and in protecting these goods from attack by microorganisms. U.S. Pat. No. 5 3,506,720 primarily deals with the use of these patented ether compounds in laundering solutions in which the halogenated hydroxy-diphenyl ethers exist in solution as phenolic salts in a basic medium.

SUMMARY OF THE INVENTION

It is therefore one of the objects of this invention to provide a liquid detergent system in which the active bacteriostat, namely, 2,4,4'-trichloro-2'-hydroxy-diphenyl ether exists as a phenol in solution. This is accomplished by solubilizing the above compound with a solution of sodium lauryl ether sulfate. The resulting liquid detergent system has a pH of about 7-8 which consequently produces a liquid detergent system having superior bacteriostatic properties.

DESCRIPTION OF PREFERRED EMBODIMENTS

The liquid detergent system of this invention consists essentially of the following components:

nide. Additionally, quaternary ammonium germicidal agents or microbiologically active ingredients based on phenolic derivatives have been employed for the above purpose.

Recently, U.S. Pat. No. 3,506,720 issued Apr. 14, 1970 disclosing halogenated hydroxy-diphenyl ethers

50 In addition the above liquid detergent system may contain the usual additives such as optical brighteners, perfumes and antiredeposition agents.

A preferred range for the above components is as follows:

	% By Weight
1. Triethanolamine linear dodecyl benzene sulfonate (40% active in an aqueous solution)	30 - 35
2. Sodium lauryl ether (3 moles ethylene oxide) sulfate (57% active in 18% ethanol and the remainder water)	10 - 15
3. Dimethyl cocoamine oxide (40% active in water)	1.40 - 1.80
4. Formula I as above.	1 - 3
5. Coconut fatty acid diethanolamine condensate	0.5 - 1.5
6. 2,4,4'-trichloro-2'-hydroxydiphenyl ether	0.60 - 0.80
7. Water	Sufficient quantity to make to 100%

The above liquid detergent system has the ability to reduce clothes odor that is brought about by bacterial degradation after the garment has been washed or during wear. The system has the ability to deposit the active anti-bacterial agent onto a fabric during a washing operation for effective deodorant activity.

A preferred method of preparation is to solubilize the 2,4,4'-trichloro-2'-hydroxydiphenyl ether with sodium lauryl ether sulfate separately and then to add this so called "pre-mix" solution to the other components of the novel laundering composition of this application. Complete solubility of the pre-mix solution is indicated when the pre-mix solution is substantially clear. The pH of the pre-mix solution after solubilization ranges from about 8.4 to 8.7.

Triethanolamine linear dodecyl benzene sulfonate (40% active in an aqueous solution) is added in a vessel, distinct from the pre-mix solution, to water with moderate agitation. Optical brighteners or other optional compounds may be added at this point. The pre-mix solution which contains 2,4,4'-trichloro-2'-hydroxydiphenyl ether solubilized in sodium lauryl ether sulfate is then added accompanied by agitation and the remaining ingredients of the composition are then added. This method of preparation provides for the solubility of the bacteriostatic component and is the method employed in the preparation of the composition illustrated in Example 1. This method also provides a liquid detergent composition that has superior stability properties.

The following Examples further illustrate this invention.

EXAMPLE 1

This Example illustrates the preparation of the laundering composition of this application. It also illustrates the necessity of employing sodium lauryl ether sulfate to keep 2,4,4'-trichloro-2'-hydroxyphenyl ether in solution.

Table I

Components	% BY WEIGHT						
	A	B	C	D	E	F	G
Water	49.9	81.9	56.4	50.0	51.5	50.9	51.9

*Necessary to obtain solubility of the active antibacterial agent.

EXAMPLE 2

Compositions A-G, in Example 1 were used to test residual bacteriostatic activity on various types of cloths as described below.

Terg-O-Tometer tests runs were made under the following conditions:

2g/1000 ml use concentration of composition.

70°F water temperature.

100 rpm.

60

Reflectometer (L scale) to ascertain cleaning results.

Machine Washing — 121g. of the composition as shown in Example 1 per 16 gallons of water in an automatic washer. Reflectometer readings were taken as described above.

Table IV summarizes the results obtained. Anti-bacterial activity of the garments washes was measured as in Example 2. Table V summarizes the results obtained.

10 min. wash time.

Cloth Load - U.S. Testing 4 x 8 inch cloths
Type - 2 Cotton, 2 Spun Nylon, 3 Dacron/Cotton,
2 Wool Flannel.

5 Total weight of cloth per bucket about 22.5g.
After rinsing and drying, the cloth swatches were subjected to testing for bacteriostatic activity via the Agar Plate Test (USDA Circular No. 198; 1931). The following "zones of inhibition" were observed against S. aureus and E. coli.

Table II

Zones of Inhibition (mm) on S. aureus	Composition of Example 1						
	A	B	C	D	E	F	G
Cotton	29	19	29	28	28	25	19
Nylon	19	15	23	21	17	27	22
Dacron/Cotton	27	21	28	20	22	25	27
Wool	15	15	17	12	14	13	21

Table III

Zones of Inhibition (mm) of E. coli	Composition of Example 1

*Clear zone surrounding the fabric with very slight areas of growth

NOTE:

Garments which were hand washed were done separately.

Machine washing consisted of a three (3) pound load of mixed garments.

Wool sweaters were washed separately by hand and by machine.

EXAMPLE 4

Bacteriostatic studies were conducted on a liquid system similar to Example 1 with the exception that the formulation contained tetrapotassium pyrophosphate and no perfume. Standard zones of inhibition were conducted as in Example 2. Table VI illustrates these compositions. Table VII illustrates the results.

TABLE VI

Example 4 - Compositions	Parts of Composition			
	A	B	C	D
Triethanolamine linear dodecyl benzene sulfonate (40% active in an aqueous solution)	32.00	32.00	32.00	32.00

60 What is claimed is:

1. A liquid detergent formulation which comprises the following components:

Triethanolamine linear dodecyl benzene sulfonate

0.1 - 50%

Sodium lauryl ether sulfate where the number of ethoxy groups is three

0.1 - 20%

Dimethyl cocoamine oxide

0.1 - 2%

65

Amphoteric coconut acid derivative having the following formula:

wherein R is a mixture of hydrocarbon radicals ranging from about 10 to about 18 carbon atoms and M is hydrogen or an alkali metal.

an alkali metal.
Coconut fatty acid diethanolamine
condensate
2,4,4'-trichloro-2'-hydroxydiphenyl ether
Ethanol
Water

Water

- 0.1 – 4%
- 0.1 – 2%
- 0.10–1.00%
- 0.1 – 10%
- Sufficient quantity to make to 100%

fate and wherein the pH of the system is about 7 to about 8.

2. A liquid detergent system according to claim 1 wherein the components have the following ratios according to their percent by weight:

	% By Weight
10	Triethanolamine linear dodecyl benzene sulfonate (40% active in an aqueous solution) 30 - 35
10	Sodium lauryl ether (3 moles ethylene oxide) sulfate (57% active in 18% ethanol and the remainder water) 10 - 15
10	Dimethyl cocoamine oxide (40% active in water) 1.40 - 1.80
15	Amphoteric coconut acid derivative 1 - 3
15	Coconut fatty acid diethanolamine condensate 0.5 - 1.5
15	2,4,4'-trichloro-2'-hydroxydiphenyl ether (97% minimum activity) 0.60 - 0.80
	Water Sufficient quantity to make to 100%

3. A liquid detergent system according to claim 1 wherein M of the amphoteric coconut acid derivative is an alkali metal.

* * * *
